Primary Examiner — Prabhakar Deshmukh(74) *Attorney, Agent, or Firm* — Phillip E. Walker; Bradley(57) **CLAIM**

What is claimed is the ornamental design for a latch handle, as shown and described.

DESCRIPTION

FIG. 1 is a left front perspective view of a latch handle showing our new design, shown in closed position;
FIG. 2 is a right front perspective view thereof;
FIG. 3 is a front elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a rear elevational view thereof;
FIG. 9 is a left front perspective view thereof, shown in an open position;
FIG. 10 is a right front perspective view of FIG. 9;
FIG. 11 is a front elevational view of FIG. 9;
FIG. 12 is a rear elevational view of FIG. 9;
FIG. 13 is a left side elevational view of FIG. 9;
FIG. 14 is a right side elevational view of FIG. 9;
FIG. 15 is a top plan view of FIG. 9; and,
FIG. 16 is a bottom plan view of FIG. 9.
The broken lines environment is for illustrative purpose only and forms no part of the claimed design.
